UNITED STATES PATENT OFFICE.

JOHN ROSSI, OF NEWCASTLE, INDIANA.

WIRE-WORKING TOOL.

SPECIFICATION forming part of Letters Patent No. 769,023, dated August 30, 1904.

Application filed April 6, 1904. Serial No. 201,833. (No model.)

To all whom it may concern:

Be it known that I, JOHN ROSSI, a citizen of the United States, residing at Newcastle, in the county of Henry and State of Indiana, have invented certain new and useful Improvements 5 in Wire-Working Tools, of which the following is a specification.

Heretofore in forming loops on the ends of wires there has been a considerable waste of 10 material due to the fact that a short piece of wire, averaging perhaps six inches in length, has been required for the purpose of performing such final operation and has afterward been broken off and thrown away. In the 15 manufacture of piano-wires, where the product amounts to thousands of wires per day, this waste is a material item and adds appreciably to the cost of production.

It is the object of my invention to produce 20 a tool by means of which these loops can be formed in a manner which admits of using the entire wire and leaving no waste whatever; and said invention consists in a tool for the purpose, as will be hereinafter more particularly described and claimed.

Referring to the accompanying drawings, which are made a part hereof, and on which similar reference characters indicate similar parts, Figure 1 is a perspective view illustrating a tool embodying my said invention as it appears when seen from the front side; Fig. 2, a similar view as it appears when seen from the rear side; Fig. 3, a top or plan view thereof; Fig. 4, a horizontal sectional view at the 35 point indicated by the dotted line 4 4 in Fig. 6; Fig. 5, a front elevation; Fig. 6, a side elevation; Fig. 7, a central vertical sectional view as seen when looking in the direction indicated by the arrows from the dotted line 40 7 7 in Fig. 5; Figs. 8 and 9, elevations, on an enlarged scale, of the facing or operative surfaces of the upper or operative ends of the jaws respectively; Fig. 10, a detail horizontal sectional view through said jaws at the point 45 indicated by the dotted line 10 10 in Fig. 5; Fig. 11, a detail sectional view as seen when looking in the direction indicated by the arrows from the dotted line 11 11 in Fig. 10 and illustrating the cranked position of the part

52 by means of dotted lines; and Fig. 12, a 50 sectional view of the nut 32.

My improved tool is adapted to be used in conjunction with an ordinary twister, (not shown,) by means of which the wires after being placed in my said tool are properly twisted. 55 Said tool in use should preferably be secured upon the end of a suitable bench or table, of which a fragment 21 appears in the drawings and to which the base 22 of my improved tool is shown as secured by a bolt 23. 60 To this base are secured the two principal jaws 24 and 25 by means of four bolts 26, 27, 28, and 29, which pass through suitable holes in the base and are tapped into the jaws. The lower bolts 26 and 28 are shown as fitting approximately closely in the holes in the base, through which they pass, while the holes through which the upper bolts 27 and 29 pass are of sufficiently larger diameter than said bolts to permit some movement of the jaws toward and from each other, said movement being, however, limited by the difference between the diameters of the bolts and of the holes in question. These jaws are normally held apart or away from each other by suitable means, as a spring 30, and 75 they are drawn toward each other by a clamping-screw 31, which passes through said jaws and enters a nut 32 at one end, while it has a shoulder at 33 and is provided with a crank-handle 34 or other appropriate means of turning it at the other end. The movement of this crank-handle in operation is a limited one, as the distance the jaws need to be moved is very short. The position of the crank-handle has much to do with the speed at which 80 the operation can be performed, and I am able to precisely adjust this speed by the following means: Upon the face of the jaw 25, against which the nut 32 bears, I put a stud 35, and in the face of the nut which is in contact with said jaw I form a series of holes 36, any one of which may fit over said stud. In practice I turn this nut to just the point required to bring the crank-handle into the most convenient position for the operator (in 85 performing the work of bringing the clamping-jaws onto the wire in operation) and engage it with the stud at that point. As a 90 95

2
movement of half a turn or less of the crank-handle is all that is required in loosening and tightening the jaws, it will be seen that a very accurate adjustment may easily be made. As 5 the tool is adapted to be used with wires of several different sizes, a separate adjustment is to be made for each size of wire.

Secured to the front faces of the jaws 24 and 25 are other jaws, 41 and 42, said jaws 10 being held in place by pivot-bolts 43 and 44. The jaw 41 at its upper end rests at one side against the stop 45. Its upper end is normally held away from the jaw 24, to which it is connected by a spring 46. It is adapted to 15 be drawn against said jaw 24 by means of a clamping-screw 47, whose head 48 bears against the outer surface of said jaw 41, and upon the other end of said screw is the nut 49, which preferably has a crank-handle 50. 20 The head 48 of the clamping-screw 47, like the nut 32, has a series of holes each of which is adapted to engage with a stud 51 on the adjacent face of the jaw 41, and by a manipulation similar to that described as being suitable to the nut 32 the position of the cranked 25 nut in operation may be adjustably determined and the most convenient relation of the parts for purposes of operation thus secured.

The jaw 42 is adapted to be moved toward 30 and from the jaw 41 by means of a crank 52, (or cam,) mounted in the adjacent jaw 25 and which extends through a suitable opening 53 in said jaw 42, said crank or cam being turned as required by means of its handle 54. As 35 will be presently more fully explained, the operative distance between the jaws 41 and 42 needs to be very exact in order to secure the best results and needs to be varied to fit the various sizes of wire, and therefore 40 the jaw 42 needs an adjustable stop. This I have provided in the form of a wedge-shaped intermediate part 55, (see especially Fig. 4,) which is prolonged into a threaded extension 56, upon which I place the nut 57. This nut 45 has an annular groove and rests in a suitable bearing 58, shown as extending up from the base 22, so that turning the nut will force the part 55 positively in one direction or the other, and thus the position and point of contact of the jaws and said part may be accurately determined.

In operation my invention is used as follows: The end of the piece of wire W (see Fig. 1) upon which the loop is to be formed is inserted 55 between the jaws 24 and 41, with its end in contact with the stop 45, the distance from said stop 45 to the opposite edges of the jaws 41 and 24 being exactly that of the length of wire required to form the final coils in producing 60 the loop. The jaw 41 is then drawn toward the jaw 24 by means of the clamping-screw 47 and nut 49, operated by its crank-handle 50. The wire is then bent at right angles and extended out in front of this tool the 65 distance desired, which is determined by the

position of the twister, (not shown,) and thence turned back and passed between the two main jaws 24 and 25. These jaws are then clamped firmly onto the wire by means of the clamping-bolt 31, operated by the crank-handle 34. The first twisting operation is then performed by the twister with the wires thus held firmly in position by means of my improved tool. The said clamping-jaws are then loosened. Then the jaw 42 is thrown 70 forward toward the jaw 41 by means of the cam 52, operated by its handle 54, the limit of its movement being determined by the position of the wedge-shaped stop 55, as before explained. This brings the partly-formed 75 structure into the precise relation required for the finishing operation—viz., the final winding of the end of the wire in a close coil about its strand. A further revolution of the twister (not shown) accomplishes this and 80 winds up the small projecting end of the wire, (which has in the previous operation been held between the jaws 41 and 24 and against the stop 45,) which, as above explained, is just long enough to form the required number 85 of turns. It will be seen, therefore, that the wire is completely used up and there is no waste of wire whatever in producing the structure required. I am also able to produce these wires much more rapidly than has been 90 possible by the old methods, and thus by means of this tool I secure both economy of material and increased production.

Having thus fully described my said invention, what I claim as new, and desire to secure 95 by Letters Patent, is—

1. The combination, in a tool for forming loops on wires, of a base, a pair of jaws pivotally secured thereto, a second pair of jaws secured to the first pair, means for operating 105 the main jaws toward and from each other, means for operating one of the second jaws toward one of the first, and means for operating the second jaw of the second pair toward and from its fellow.

2. The combination, in a tool for forming loops on wires, of a base, a pair of jaws pivotally secured thereto for clamping the main wire during operation, and a second jaw secured to one of said jaws for clamping the 115 wire end during operation.

3. The combination, in a tool for forming loops on wires, of a pair of jaws between which the main wire may be clamped; a jaw secured to one of said main jaws between which and said main jaw the end of the wire may be clamped, and a stop against which the end of the wire may be placed and whereby the length of said wire end may be determined.

4. The combination, in a tool for forming 125 loops on wires, of jaws movable toward and from each other, a screw and a nut for moving said jaws, and engaging means between one member of said moving means and one of said jaws whereby its position may be accu- 130

rately and adjustably determined and the most convenient position of said moving means for the operator thus secured.

5. The combination, in a tool for forming loops on wires, of a base, two main jaws pivotally secured to said base, two other jaws pivotally secured to the first-named jaws, means for operating said jaws, and an adjustable stop arranged between the two second-named jaws whereby the distance which shall

remain between said second-named jaws when operated may be adjustably determined.

In witness whereof I have hereunto set my hand and seal, at Newcastle, Indiana, this 1st day of April, A. D. 1904.

JOHN ROSSI. [L. S.]
